FRANK HOLT, OF CHICAGO, ILLINOIS, ASSIGNOR TO STROMBERG MOTOR DEVICES COMPANY, OF CHICAGO, ILLINOIS, A CORPORATION OF ILLINOIS.

PROCESS FOR MAKING CARBURETOR FLOAT CUPS.

Application filed April 29, 1925. Serial No. 26,626.

This invention relates to a process and dies for making a sheet metal cup for accommodating the fuel level controlling float in a carburetor and also the fuel supply controlling valve. In order to reduce the space and weight, the diameter of these cups is usually made just large enough to accommodate the cylindrical float, and a vertically extending outward deflection or bay is provided at one side of the cup for accommodating the fuel outflow controlling valve which is usually adjustable at the top of the cup and engages at its lower end in a valve seat at the cup bottom. Heretofore, these float cups have usually been an integral part of the carburetor body casting, and therefore required considerable finishing and structural work. It has been found that by using sheet metal in the construction of these float cups, the manufacture of a carburetor can be greatly simplified and the cost reduced, and the object of this invention is to provide an improved process for making the sheet metal cup and particularly an improved step for forming the deflection for a valve accommodating bay at the side of the cylindrical cup.

The construction of the cup is started from a flat piece of sheet metal which is drawn and subjected to die operation until there results a structure comprising a cylindrical body with a cover seating embryo flange at the top, and the invention is concerned particularly with a die process for reducing the diameter of this embryo cup and providing thereon the valve accommodating lateral deflection or bay. Briefly defined, the process consists in squeezing or compressing the body of the embryo cup between opposed die members having semicylindrical pockets of a radius equal to that of the desired radius of the finished cup, and the die members have opposed recesses into which the surplus or deflected metal is forced to form the wall for the bay or channel which receives the fuel valve. The pressure dies cooperate with a core die which extends into the cup and defines or patterns the finished shape of the body.

My improved process and the dies are fully illustrated on the accompanying drawings, in which—

Fig. 1 is a plan view of the base or lower die part;

Fig. 2 is an under side view of the upper die structure;

Fig. 3 is a sectional plane 3—3 of Fig. 1;

Fig. 4 is a sectional view on plane 4—4 of Fig. 3;

Fig. 5 is a sectional view on plane 5—5 of Fig. 3;

Fig. 6 is a plan view showing the embryo cup between the die members;

Fig. 7 is a side elevational view of the finished cup; and

Fig. 8 is a sectional view on plane 8—8 of Fig. 7.

The lower die structure, designated as a whole A, comprises the base 10 having the opening 11 for receiving the supporting lug 12 of the supporting block 13. At opposite sides of the supporting block, die blocks 14 and 15 are slidable on the base 10, and are confined by the engagement of their side flanges 16 in recesses 17 and plates 18 overhanging the recesses. As the body of cup to be formed is cylindrical, the die blocks have the semi-cylindrical die pockets 19 and 20, respectively, the supporting block 13 being also cylindrical and of the same radius as the die pockets. The finished cup is shown in Fig. 7, it comprising the cylindrical body part 21, the lateral vertically extending deflection or bay 22, and the top or cover supporting flange 23. The radius of the supporting blocks and die blocks is equal to that of the body part of the finished cup.

Extending transversely on the base 10 outside of the die blocks 14 and 15, are the walls 24 and 25 and from each of these die blocks rods 26 extend through openings in the respective walls between the outside of which walls and the heads 27 on the rods compression springs 28 encircle the rods, and these springs tend to pull the die blocks outwardly into open position to receive the work which is to be formed. Pins 29 secured in and extending from the die blocks, limit the outward movement of the die blocks by abutting against the walls.

The upper outer corners of the die blocks 14 and 15 are beveled and have rectangular recesses 30 for the wearing or wedge surface plates 31 held in place by screws 32.

The upper die structure comprises the base 33 from which extend downwardly the rectangular die plungers 34 and 35, these plungers being adjustably held in place by

set screws 36 engaging their lugs 37 which extend into the base 33. On their inner sides, these die plungers are cut away to leave the inclined or wedge surfaces 38 and the rectangular ends 39, the slope of the wedge surfaces being the same as that of the plates 31 on the die blocks 14 and 15. The wedge surfaces 38 are vertically aligned with the wedge plates, and when the die structures 5 come together the plungers travel downwardly between the walls 24 and 25 and the outer sides of the die blocks, the openings 40 in the base 10 receiving the ends 39 of the die plungers. After the wedge surfaces 38 10 come into engagement with the wearing plates 31, further downward movement of the upper die structure will cause wedging engagement between the wedge surfaces and powerful inward movement of the die blocks 14 and 15 to shape and form the cup structure between the die blocks. The diameter 20 of the embryo cup, shown in Figs. 3 and 5 and in dotted lines in Fig. 6, is greater than that of the finished cup shown in Fig. 7. The 25 supporting block 13 has the lateral vertically extending deflection or substantially semi-circular lug 41 conforming in shape to the deflected part 22, which is to be formed in the embryo cup. The adjacent corners of 30 the die blocks 14 and 15 are cut away to leave the die pockets or recesses 42 and 43, which cooperate with the lug 41 to shape the deflection 22. The embryo cup is seated 35 on the block 13 between the die blocks 14 and 15 and with its flange overhanging the die block, as shown in Figs. 3, 5 and 6. When the upper die structure is then forced 40 downwardly into the lower die structure, the wedge surfaces referred to will powerfully shift the die blocks 14 and 15 against and around the body of the embryo cup to squeeze and contract the body part and shift the metal into the die recesses 42-43. The 45 metal of the cup is guided by the mandrel 44 secured to and extending from the base 33 of the upper die structure, the diameter of this mandrel being that of the finished cup. The mandrel has also the substantially semi-circular projection or lug 45 extending vertically thereon and in alignment with the lug 41 on the supporting block 13. Thus, 50 when the die blocks 14 and 15 are forcibly brought together, the metal of the embryo cup will be drawn around the mandrel and

around the lug 45 to form the finished cup 55 with the deflection 22 which provides space for the fuel controlling valves. As shown in Fig. 2, the lug 45 may form part of an insert 46 for the mandrel, so that after one insert is worn out, another can be readily applied. 60

An annular plate 47 surrounds the mandrel and is secured against the under side of the base 33. Between this plate and a lower annular plate 48 compression springs 49 are 65 interposed which tend to hold the plates apart, and guide pins 50 which hold the plates in registration. When the upper die structure is brought down, the lower plate 48 will engage against the flange of the 70 embryo cup and will force and hold the cup in position between the die blocks while the cup is being formed. When the upper die structure is then withdrawn, the plate 48 will be held pressed against the flange a sufficient length of time to permit the mandrel 75 to loosen itself from the formed cup and be readily withdrawn therefrom. As soon as the upper die structure starts upwardly, the springs 28 will draw the die blocks 14 and 15 away from the cup and the finished cup can then be readily withdrawn. 80

By use of my improved process and dies in the formation of the float cup, the cost of manufacture of carburetors can be materially reduced and the strength greatly increased and the weight decreased. 85

I claim the following:—

1. The process of forming a longitudinally extending bay in the side of a cylindrical sheet metal cup which consists in constricting the cup in a single operation radially from top to bottom to smaller diameter and at the same time forcing the resulting fold laterally to form the bay. 90

2. The process of forming a sheet metal cylindrical cup of a certain diameter into a cylindrical cup having a reduced diameter and a longitudinally extending outward deflection, which consists in radially contracting the cup from top to bottom in a single operation to the desired diameter and, at the same time, forming the surplus material into the desired deflection. 100

In witness whereof, I hereunto subscribe my name this 22nd day of April, 1925. 105

FRANK HOLT.
